CONTROLLING MECHANISM FOR REVERSING-ENGINES.

1,130,993.

Specification of Letters Patent.

Patented Mar. 9, 1915.

Application filed June 17, 1914. Serial No. 845,675.

To all whom it may concern:

Be it known that I, WALTER W. MCBANE, a citizen of the United States, residing at Youngstown, in the county of Mahoning and State of Ohio, have invented certain new and useful Improvements in Controlling Mechanism for Reversing-Engines, of which the following is a specification.

10 This invention relates to a controlling mechanism for reversing engines, either simple or compound, particularly of the type employed for driving one-train rolling mills, and has special reference to a novel 15 single lever control arrangement therefor.

In rolling mills, particularly mills of the type commonly known as "one-train mills" wherein the blank is passed back and forth through the same train of rolls, it is especially desirable that a simple and effective mechanism be provided whereby the reversing gear of the driving engine can be easily and quickly actuated. In engines of this character, in order to obtain the most economical use of steam, it is necessary that the 20 cut-off be governed largely by the pressure of steam in the cylinder, or in other words by the opening and closing of the throttle, and it is the purpose of the present invention to automatically operate the cut-off as the throttle opens and closes. These driving engines in starting, or where a slow hard pull is necessary, must have a long cut-off with the throttle valve or valves, as the case

30 may be, only partly opened. As the load increases, a more economical working of the driving fluid is secured by using the full pressure of the working fluid and regulating the amount of power delivered by 35 changing the point of cut-off in the cylinders, than by throttling the pressure and using the full cut-off. While it is theoretically possible to secure these conditions with the ordinary two-lever control mechanism 40 now in use on most reversing engines, it is a very difficult task and requires a skilful operator. Investigation shows that it is the common practice, particularly with reversing engines, for rolling mill service, for the 45 operator to throw the reversing lever to full over or under position, as the case may be, and regulate the amount of power delivered by means of the throttle or throttles, thereby losing, for the greater part, the expan-

sive effect of the working fluid and its accompanying economy.

Accordingly, it is the primary object of the present invention to overcome this difficulty by an interconnection of the engine throttle and the reversing and cut-off mechanism, by which all the conditions to be desired in this connection are automatically attained and controlled while running in either direction and for all positions of the throttle or throttle valves and the reversing and cut-off mechanism. That is to say, the present invention contemplates novel means for automatically and synchronously operating jointly the throttle and cut-off of the driving engine.

70 A further object of the invention is to provide a thoroughly practical device that is controlled by means of a minimum number of manually set devices, thereby greatly facilitating the operation of the driving engine, and at the same time accomplishing other advantageous results.

With the above and other objects in view which will more readily appear as the nature of the invention is better understood, 80 the same consists in the novel construction, combination and arrangement of parts hereinafter more fully described, illustrated and claimed.

A preferred and practical embodiment of 85 the invention is shown in the accompanying drawings, in which—

Figure 1 is a top plan view of the reversing mechanism showing the single lever control. Fig. 2 is a side elevation of the construction shown in Fig. 1. Fig. 3 is a longitudinal sectional view of the apparatus. Fig. 4 is a diagrammatic view showing the single control lever moved to one side of its neutral position so that the manually set distributing valve will admit steam to one of the secondary piston cylinders of the operating unit. Fig. 5 is also a diagrammatic view illustrating the position of the parts shown in Fig. 4 at the end of one stroke of 95 the prime actuating piston. Fig. 6 is an enlarged fragmentary sectional view of one of the operating pistons of the operating unit, and a portion of the piston chamber therefor.

105 Similar reference characters designate corresponding parts throughout the several figures of the drawings.

With particular reference to the details of construction as shown in the several figures of the drawings, it will be observed that the entire reversing mechanism rests upon a suitable base 1. At one end of the base there is arranged a primary piston cylinder 2, and a combined superimposed double valve chest and valve housing designated in its entirety by the reference character 3. At the opposite end of the base there is located an open-ended guide member 4 which supports a secondary piston cylinder 5. This cylinder 5 and the said valve chest 3 are connected by means of steam conducting pipes 6 and 7 which will hereinafter be more fully described.

The double valve chest 3 includes a distributing chamber 8 and a cut-off valve chamber 9 separated by a partition wall 10, the latter having a central steam inlet passage 11 fed from the steam supply pipe 12. From the inlet 11 the steam is permitted to enter the chambers 8 and 9 through suitable ports 13 and 14 respectively, and the ends of the chambers 8 and 9 communicate with each other through the exhaust ports 15 and 16 shown in Fig. 3 of the drawings. The cut-off valve chamber 9 is also in communication with the primary piston cylinder 2 by means of the end ports 17 and 18, which are alternately opened and closed by means of an elongated cut-off valve 19 having at its ends the valve heads 20 and 21 respectively. The said cut-off valve 19 has connected to one end thereof a stem 22 which extends exteriorly of the steam chest and is pivoted as at 23 to a cut-off controlling lever 24. This cut-off control lever 24 is pivoted at one end as at 25 to a fulcrum rod 26, one end of which latter is pivoted as at 27, Fig. 2, to one arm 28 of a bell crank lever 29 which is rotatably mounted on a quadrant shaft 29^a journaled in a supporting bracket 30, and also provided with an operating pinion 31. The pinion 31 meshes with a segment 32 carried by an operating lever 33 which is also pivoted in a portion of the supporting bracket 30, as at 34. The other arm 35 of the bell crank 29 is at right angles to the arm 28, as clearly shown in Fig. 2 of the drawings, and is pivotally connected with a suitable link 36 which in turn is pivotally connected at 37 with the valve stem 38 of a manually-set distributing valve 39, which is similar in construction to the cut-off valve 19 and provided at its ends with valve heads 40 and 41 respectively.

Mounted within the primary piston cylinder 2 is a prime-actuating piston 42 having the piston rod 43 extending through the cylinder head 44 and connected at its outer end with a reciprocating cam yoke 45. At this point, it may be noted that the end of the reciprocating cam yoke 45 which connects with the piston rod 43 carries an angular

bracket arm 46 which is provided at its lower end with a suitable angularly disposed pivot lug 47. A movable connection between the bracket arm 46 and the throttle controlling lever 24 is provided by means of the link 48 pivotally connecting with the lower end of the said lever 24 and also with the lug 47.

In connection with the reciprocating cam yoke 45, it will be observed that the same is preferably of elongated rectangular form, and at the end opposite its connection with the piston rod 43 has pivotally attached thereto a throttle valve rod 49 which is joined in a suitable manner with the ordinary throttle valve of an ordinary rolling mill driving engine. The said cam yoke 45 is provided with oppositely arranged slide-shoes 50 which slidably bear against the upper and lower sides of the guide member 4 through which the yoke freely operates, and the side frame members 51 of said yoke are provided with inwardly projecting wedge-shaped cam elements 52 and 53.

Referring to the main operating unit, it will be observed that the steam pipes 6 and 7 communicate at one end with the distributing chamber 8 through the ports 6^a and 7^a respectively, while the opposite ends of said pipes communicate with the said secondary piston cylinder 5 of the operating unit through the inlet ports 5^a and 5^b.

The secondary piston cylinder 5 is provided with two oppositely arranged bushing-lined piston chambers 54 and 55 respectively, each of which is closed at its outer end by a removable cylinder head 56 held in place by a suitably mounted screw 57 and formed with an inside plunger receiving socket 57^a. Furthermore, each of these chambers 54 and 55 is formed with an internal stop shoulder 58. This shoulder opposes and serves to arrest the movement in one direction of the head 59 of a lever-operating piston 60, there being one of said pistons reciprocally mounted in each of the chambers 54 and 55.

The operating pistons 60 are of duplicate construction. Each includes the head portion 59 and a tubular stem portion 61, (Fig. 6), the latter slidably receiving an auxiliary headless and free piston plunger 62, and what may be termed the inner end portions of the tubular stem 61 of the pistons 60 are adapted to be projected by steam pressure into a central guideway 63 formed by an annular enlargement of the central interior portion of the secondary piston cylinder 5. This central guideway 63 also accommodates for movement therein a sliding cross head 64 which is interposed between, and therefore co-operates with, both of the operating pistons 60. This sliding cross head 64 includes a center block 65 carrying a transversely extending pin 66 to the outer ends 120 125 130

of which are pivotally attached the arms 67 of a pair of bell crank transmitting levers 68. These bell crank levers 68 are fulcrumed on a pivot shaft 69 which extends transversely of the guide member 4, and has its journal bearings in the side walls thereof. The side walls of the guide member 4 are cut away as at 70 to provide a clearance opening for a tappet roller 71 which is mounted on an axle member 72 connecting the outer ends of the arms 73 of the opposite bell crank levers 68. Thus, it will be apparent that this arrangement of the tappet 71 carried by the bell crank levers 68, permits the said tappet to be thrown into and out of contact with the cams 52 and 53 of the reciprocating cam yoke 45. Secured to the shaft 69, at one side of one of the bell crank levers 68, and in the same relative radial position with the arm 67 of said lever 68, is a reversing and cut-off arm 74 which is connected by the link 75 and other usual intermediary connections, either with the usual reversing and cut-off mechanism of the ordinary rolling mill driving engine to operate the same, or their auxiliary operating mechanisms.

Referring to the general operation of the apparatus, it will be observed that the working fluid or live steam is conducted into the double valve chest 3 by means of the supply pipe 12, the same passing into the inlet 11 in the partition wall 10 from whence it makes its way by means of the ports 13 and 14 to the distributing valve chamber 8 and the cut-off valve chamber 9. It will, of course, be understood that the further course of the working fluid from these chambers is controlled entirely by the valves 39 and 19. That is to say, whether or not the steam is permitted to enter either or both of the cylinders 54 and 55 of the main operating unit depends entirely upon the position of the distributing valve 39, while the admission of steam to first one side and then the other of the piston head 42 is also entirely controlled by the position of the cut-off valve 19.

It will be observed that when the control lever 33 is in neutral position at A, the distributing valve 39 is in the center of its chamber 8, as shown in Fig. 3, so that the heads 40 and 41 thereof are beyond the ports 6^a and 7^a, and thereby uncovering them so that steam coming through the port 13 from the inlet 11 can make its way around the stem of the distributing valve and pass into both of the steam pipes 6 and 7. These pipes 6 and 7 communicate with the secondary piston cylinders 54 and 55, and in this position of the distributing valve each of said chambers receives an equal pressure of the working fluid, thus forcing the two pistons 60 toward each other until they come in contact with the stop shoulders 58, and at the same time clamp the cross head 64 in

the central portion of the guideway 63. At this point, it may be noted that the plungers 62 being of equal diameter and smaller than the pistons 60 cannot move the cross head from its central position, while the pressure 76 is the same in both cylinders. Thus, it will be apparent that when the cross head 64 is in its central position, it will maintain the arms 67 of the bell crank 68 in the relatively perpendicular position shown in Fig. 3, so 75 that the arms 73 thereof which carry the tappet roller 71 will be in a relatively horizontal position, and said roller 71 will be out of the path of the cams 52 and 53 of the reciprocating cam yoke. While the bell 80 crank levers 68 are in the neutral position described, it will also be observed that the reciprocating cam yoke 45 is at the end of one part of its stroke. And, the cut-off valve 19 is then in such a position that steam 85 can pass from the inlet 11 through the port 14 around the stem of the valve and down into the primary piston cylinder 2 through the port 18, thus holding the piston head 42 at the one end of its stroke. When the control lever 33 is moved to either position B or C, the distributing valve 39 will be moved to a position whereby either the cylinder 54 or the cylinder 55 is connected to the exhaust, leaving the other cylinder open to 90 the working fluid. This movement changes the position of the cross-head 64 which in turn changes the position of the reverse and cut-off lever 74 through the medium of the bell cranks 68, and also carries the roller 71, 100 mounted on the outer ends of arms 73 of the bell cranks 68, over against cam 52 or 53, as the case may be, of the cam yoke 45, and in this position we have the maximum cut-off. Any further movement of the lever 33 105 away from A admits pressure to the top of piston head 42, forcing the cam-yoke 45 outwardly, which, through the movement of valve-rod 49, opens the throttle valve of the engine to the admission of steam, and when the lever 33 reaches the point D or E, the movement of the rod 49 will be sufficient to give the throttle valve a substantially full 110 open position, and any further movement of the lever merely keeps the throttle open and forces the cam yoke farther out, and when it reaches F or G the cut-off is again at its maximum point. This outward movement of the cam yoke 45 also brings cam 52 or 53 into operation upon the roller 71, the effect 115 of which is to shorten the cut-off, through the medium of the bell-cranks 68, until the highest point of the cam passes under the roller, or to about 40% or 45%, after which the cut-off is again lengthened as the cam 120 passes farther under the roller, and when the cam yoke 45 reaches its full outward stroke, we again have the maximum cut-off, as shown in Fig. 5.

As has been previously pointed out, any 130

movement of the control lever 33 from its central position toward its over or under position changes the position of the manually set distributing valve 39 and also changes the position of the fulcrum point 25 at the junction of the cut-off valve lever 24 and fulcrum rod 26, and for the purpose of illustrating the general movement of the parts of the present mechanism, reference is to be had to Figs. 4 and 5 of the drawings, which show in diagram two positions of the mechanism which are illustrative of the principle involved in the entire action of the apparatus for any movement of the control lever 33.

Assuming that the control lever 33 has been moved from its central position toward its partial or extreme over position, the bell crank lever 29 is moved so that the fulcrum rod 26 is pulled forward, and the distributing valve stem 38 is also pulled forward. This position of the rod 26 and valve stem 38 causes the fulcrum point 25 of the throttle lever 24 to be altered, and places the distributing valve 39 in such a position that its head 40 is at one side of the port 6^a, while the head 41 is between the port 6^a and port 6^b, thus uncovering the port 6^b so that the chamber 54 can exhaust into the chamber 8, and at the same time establishing the chamber 55 in communication through the pipe 6 with the steam inlet 11. Thus, it will be understood that steam entering the supply pipe 12 passes from the inlet 11 around the stem of the valve 39 into the chamber 55 of the secondary piston cylinder member by means of the pipe 6. The change in position of the fulcrum point 25 is such that for this setting of the control lever, the cut-off valve 22 pushes the cut-off valve 19 into such a position that communication is established between the steam inlet 11 and the rear face of the piston head 42 through the space around the shank of the valve 19 and port 17. This position of the cut-off valve 19 is such that the head 21 thereof does not cover the mouth of the port 18, thereby permitting the working fluid on the other side of the piston head 42 to exhaust through said port into the cut-off chamber 9. Accordingly, it will be understood that when the distributing valve 39 is in the position shown in Fig. 4, live steam will be admitted into the chamber 55, while the chamber 54 is in continuous communication with the exhaust. The effect of this is to force the piston 60 and its plunger 62 of the cylinder 55 outwardly against the cross head 64, thus tilting the bell cranks 68 upon their shaft 69 so that the arms 73 thereof are forced upwardly carrying with them the roller 71 which is forced into contact with the face of the cam 52.

Returning now to the cut-off valve 19 which has been permitting steam to pass behind the piston head 42, it will be obvious

that the said piston head will move forward in the cylinder 2 pushing its stem 43 out of the cylinder, and at the same time turning the control lever 24 about its fulcrum point 25. The forward movement of the piston 42 gives the reciprocating cam yoke its forward stroke, and in connection with said yoke, it will be remembered that the piston 60 and plunger 62 of the secondary piston element has tilted the bell crank lever 68 so that the roller 71 carried thereby is in contact with the face of the cam 52, and consequently the forward stroke of the cam yoke will push the bell crank back toward its neutral position against the force of the plunger 62. Thus, it will be apparent that the forward stroke of the reciprocating cam yoke moves the rod 49 that connects with the driving engine throttle valve, and also moves the link 75 to actuate the reversing gear of the driving engine. Accordingly, it will be apparent that there is accomplished an interconnection of the throttle operating mechanism and the reversing and cut-off mechanism, such that both the throttle valve or valves of the driving engine and also the reversing and cut-off mechanisms thereof have a definite related position for the various positions of the controlling lever. In this connection, it will now be noted that one motion transmitting element is the lever 75 operated by the bell cranks, and the other motion transmitting element is the cam yoke 45 having connection with the said throttle connection for the rolling mill driving engine.

The position of the bell crank levers, cam yoke, etc., at the end of the first stroke is clearly illustrated in Fig. 5, so it is obvious that the position of the various parts of the apparatus for all positions of the control lever 33 are substantially as first shown in Fig. 4, and then as shown in Fig. 5. That is to say, the diagram in Fig. 5 represents the position of the parts when the reciprocating cam yoke completes its first actuating stroke, while Fig. 4 shows the position of the parts when the yoke returns for its next stroke.

In connection with the manually set distributing valve 39, it will be noted that the same remains in its set position for the entire time that it is desired to actuate the mill driving engine through the medium of the bell crank levers which have their rollers 71 in contact with the face of the cam 52. That is to say, the valve 39 is manually set so that live steam is admitted to either one of the cylinders 54 or 55 and remains in this position throughout the operation of the apparatus. According to the illustration exemplified in Figs. 4 and 5 of the drawings, the valve 39 is set so that steam is continuously fed to the chamber 55, whereby when the cross head 64 is forced toward its central position by means of the cam 52

52 working against the roller 71 of the bell crank levers, it moves toward its central position against the force of the working fluid in the chamber 55. In other words, the 5 chamber 55 is always filled with steam during the operation of the device for this position of the control lever, thereby having the effect of a cushion or spring which always tends to force the cross head to such 10 a position that the bell crank levers are tilted to maintain the roller 71 against the face of the cam 52. It will of course be understood that when the control lever 33 is pushed to the opposite side of its center 15 position A, that is toward the under position, the valve 39 will allow steam to enter the chamber 54 and will permit the chamber 55 to exhaust. The effect of this operation of the device is to tilt the bell crank levers 68 so 20 that the roller 71 carried thereby is in contact with the face of the cam 53 instead of the cam 52 as shown in the drawing. Referring to the exhaust from the various cylinders, it will be observed that the exhaust 25 from cylinder 54, for instance, is through pipe 7 into the chamber 8 below head 41, through port 16 into chamber 9 and to drain connection 9^a. The exhaust from cylinder 55, is through pipe 7 into the opposite end 30 of chamber 8 and through port 15 into chamber 9. The exhaust from cylinder 2 is through ports 17 and 18 into chamber 9 and from there to the drain connection. Again referring to the single control lever 35 33, it will be noted as the same is still further moved as from B to D or C to E, the piston 42 will be forced to move directly in proportion to the movement of the control lever, and the throttle valve or valves of the driving 40 engine being either directly connected to the reciprocating cam yoke 45 or through a relay or operating cylinder will be opened in proportion to this movement. The movement of the piston 42 causes the cam yoke 45 to move and actuate the bell crank 45, and also actuate the reversing and cut-off lever 74 toward its central position, thus shortening the cut-off of the driving engine. The maximum point of cut-off is either at 50 the point B or C, while the shortest point of cut-off is when the highest point of either of the cams 52 or 53 is under the roller 71. As previously stated, whenever the control lever 33 has been moved to either point D 55 or E, the movement of the link 49 has been sufficient to give practically a full opening to the throttle of the driving engine, and any further movement of the lever toward points F or G will keep the throttle open 60 and lengthen the cut-off as desired by the action of the cams of the cam yoke on the roller 71 and the reversing and cut-off lever 74, until the maximum cut-off is again secured at points F or G. The relation of 65 the throttle operating mechanism and the

reversing and cut-off mechanism for the driving engine is such that when the controlling lever 33 is in mid-position, the throttle valve of the driving engine is closed and the reversing and cut-off gear is in mid-position. As the controlling lever 33 is moved a certain distance in either the over or under directions as to points B or C, the reversing and cut-off gear is thrown to the corresponding maximum position, while the 70 throttle valve remains closed, and as the lever is still further moved as to D or E, the engine cut-off is shortened to 40 or 45 per cent. while the throttle valve has practically been opened its full amount. With a still 80 further movement of the control lever as to F or G, the cut-off is lengthened, and may be lengthened to maximum if necessary, while the throttle valve remains practically in the same position. 85

In connection with the foregoing description, it will be observed that the engine controlling mechanism herein described resolves itself into what may be characterized a "main operating" unit which includes the 90 main transmitting lever for the reversing gear connection, the reciprocating motion transmitting member (cam yoke 45) for the throttle connection, and the steam actuated lever-operating pistons, and a fluid pressure 95 "actuating unit" having means for supplying steam to the lever operating pistons of the operating unit, and also having a cylinder and piston means for operating the reciprocating transmitting element or cam 100 yoke of the operating unit. Also, in combination with the operating unit and actuating units, there is associated the herein described manually adjusted setting device which simultaneously changes the position 105 of the distributing valve of the actuating unit and the position of the fulcrum lever through which motion is transmitted to the cut-off valve of the actuating unit.

It will be understood that the invention 110 is necessarily susceptible to a wide range of structural modification without departing from the spirit or scope thereof, and therefore that various changes in the minor details of construction may be resorted to 115 without departing from the scope of the appended claims or sacrificing any advantages of the invention.

I claim:

1. An engine controlling mechanism including a transmitting element for the reversing gear, a transmitting element for the throttle, said transmitting elements having parts which shiftably and reversibly interengage, a motor for operating the throttle element, and separate means for effecting one movement of the reversing element. 120

2. An engine controlling mechanism including an operating unit having transmitting elements respectively for the throttle 125

- and reversing gear, the throttle element having a shiftable actuating engagement with the reversing element, and a fluid pressure actuating unit for causing an automatic operation of said operating unit.
5. An engine controlling mechanism including transmitting elements respectively for the throttle and the reversing gear of an engine, the throttle element having actuating means for effecting a variable movement of the reversing element, separate means for automatically effecting an opposite movement of said reversing element, and a motor for automatically reciprocating the throttle element.
10. An engine controlling mechanism including transmitting elements respectively for the throttle and reversing gear of an engine, the throttle element being interengaged with the reversing element and having means for effecting a variable movement thereof, an automatic device actuating the reversing gear element in an opposite direction, and a fluid pressure actuating unit having means for actuating the throttle element.
15. An engine controlling mechanism including transmitting elements respectively for the throttle and reversing gear of an engine, the throttle element interengaging with the reversing gear element and having actuating means for effecting one movement of the latter, and a separate automatic device for actuating the reversing gear element in an opposite direction, said automatic device including means for reversing the operative relation of the reversing gear element to the throttle element.
20. An engine controlling mechanism including an operating unit having transmitting elements respectively for the throttle and reversing gear of an engine, and a reversible fluid pressure device for effecting one movement of the reversing gear element, an actuating unit including a piston and cylinder device for reciprocating the throttle element, and a manually adjusted setting device having means for controlling said reversible fluid pressure device and also for varying the cut-off of said piston and cylinder device.
25. An engine controlling mechanism including, in combination with connections respectively for the throttle and reversing gear of an engine, an operating unit having operatively interengaged transmitting elements for said separate connections, an actuating unit including a piston and cylinder device for operating one transmitting element, reversible fluid-pressure means for effecting one movement of the other transmitting element, a controlling device for said fluid-pressure means, and a manually adjusted setting device having means for simultaneously altering the position of said

controlling device and changing the operating position of the cut-off of said piston and cylinder device.

8. An engine controlling mechanism including, in combination with connections respectively for the throttle and reversing gear of an engine, an operating unit having operatively interengaged transmitting elements for said separate connections, an actuating unit including fluid pressure means for actuating one transmitting element, a duplex piston and cylinder device for effecting one movement of the other transmitting element, a distributing valve for controlling said fluid-pressure means, and a manually adjusted setting device having adjusting connections respectively with said distributing valve and the cut-off of the piston and cylinder device.

9. An engine controlling mechanism including, in combination with connections respectively for the throttle and reversing gear of an engine, an operating unit having operatively interengaged transmitting elements for said separate connections, and oppositely working alternately active pistons operatively related to one of the transmitting elements, and an actuating unit including fluid-pressure means for rendering said working pistons active, and a piston and cylinder device for operating the transmitting element for the throttle connection.

10. An engine controlling mechanism including, in combination with connections respectively for the throttle and reversing gear of an engine, an operating unit having operatively interengaged transmitting elements for said separate connections, separate piston chambers, and oppositely working alternately active pistons respectively arranged in said separate chambers and operatively related to the transmitting element for the reversing gear, and an actuating unit including fluid-pressure means for said working pistons, and a piston and cylinder device operatively connected with the transmitting element for the throttle connection.

11. An engine controlling mechanism including, in combination with connections respectively for the throttle and reversing gear of an engine, an operating unit comprising operatively interengaged transmitting elements for said separate connections, a duplex reversible piston and cylinder device operatively related to one of the transmitting elements, and an actuating unit including a valve controlled fluid-pressure means for said piston and cylinder device of the operating unit, and also including a cut-off controlled piston and cylinder device connected with the transmitting element for the throttle connection.

12. An engine controlling mechanism including, in combination with connections re-

- specitively for the throttle and reversing gear of an engine, an operating unit comprising operatively interengaged transmitting elements for said separate connections, 5 and a duplex reversible piston and cylinder device operatively related to the transmitting element for the reversing gear, an actuating unit including valve controlled fluid-pressure means for said piston and cylinder 10 device of the operating unit, and also including a cut-off controlled piston and cylinder device connected with the transmitting element for the throttle connection, and a manually adjusted setting device having 15 adjusting connections respectively with the valve for said fluid-pressure means and with the cut-off for the piston and cylinder device of the actuating unit. 13. An engine controlling mechanism including, in combination with connections respectively for the throttle and reversing gear of an engine, an operating unit comprising transmitting elements for said separate connections, interengaging parts between said transmitting elements to thereby cause a joint movement thereof in certain positions, and a duplex reversible piston and cylinder device operatively connected with one of the transmitting elements, and 20 an actuating unit including valve controlled fluid-pressure means for said piston and cylinder device, and also including a cut-off controlled piston and cylinder device connected with the transmitting element for the 25 throttle connection. 14. An engine controlling mechanism including, in combination with connections respectively for the throttle and reversing gear of an engine, an operating unit comprising a swinging transmitting lever for the reversing gear connection, and a reciprocating transmitting element for the throttle connection shiftably and reversibly interengaged with said lever, and an actuating 30 unit having means for automatically and synchronously effecting the movement of said separate transmitting elements. 15. An engine controlling mechanism including, in combination with connections respectively for the throttle and reversing gear of an engine, an operating unit having a swinging transmitting lever for the reversing gear connection, and a reciprocating transmitting element for the throttle having 35 reversely related cams for engagement with said lever transmitting element, and an actuating unit having means for automatically and synchronously effecting the movement of said separate transmitting elements. 16. An engine controlling mechanism including, in combination with connections respectively for the throttle and reversing gear of an engine, an operating unit having a 40 transmitting lever for the reversing gear connection, and a reciprocating transmitting element for the throttle connection shiftably and reversibly interengaged with the reversing gear lever, and an actuating unit including valve controlled fluid-pressure means for said respective piston chambers. 17. An engine controlling mechanism including, in combination with connections respectively for the throttle and reversing gear of an engine, an operating unit having a transmitting lever for the reversing gear, and a reciprocating cam yoke for the throttle connection, said cam yoke having reversely related cams separately having operating engagement with the transmitting lever, the operating unit also including a piston and cylinder device for moving the transmitting lever, and an actuating unit including fluid-pressure means for causing an operation of the piston and cylinder device of the operating unit, said actuating unit also including a cut-off controlled piston and cylinder device connected with the 45 said cam yoke. 18. An engine controlling mechanism including, in combination with connections respectively for the throttle and reversing gear of an engine, an operating unit including separate transmitting elements for said separate connections, oppositely arranged piston chambers, and oppositely working pistons arranged in said chambers and adapted one at a time to be operatively engaged with the transmitting element for the reversing gear, and an actuating unit including valve controlled fluid-pressure means for either simultaneously charging 50 both piston chambers with steam to maintain a neutral position of parts, or to cut off one of the piston chambers and leave the other chamber charged with steam during the operation of the mechanism, said actuating unit also including means for automatically moving the transmitting element for the throttle connection. 19. An engine controlling mechanism including, in combination with connections respectively for the throttle and reversing gear of an engine, an operating unit having a transmitting lever for the reversing gear connection, and a reciprocating transmitting element for the throttle connection operatively interengaged with the reversing gear lever, oppositely arranged piston chambers, oppositely working tubular pistons mounted within said chambers and operatively related to the transmitting lever, and steam actuated plungers mounted within the operating pistons and also operatively related to the transmitting lever, and an actuating unit including valve controlled fluid-pressure means for said respective piston chambers. 55 60 65 70 75 80 85 90 95 100 105 110 115 120 125 130

bers of the operating unit, and cut-off controlled means for actuating the reciprocating transmitting unit.

20. An engine controlling mechanism including, in combination with connections respectively for the throttle and reversing gear of an engine, an operating unit having a transmitting element for the reversing gear, which transmitting element includes 5 bell cranks carrying a cross head at one end, another reciprocating transmitting element for the throttle connection having reversely related cams which engage the bell cranks at one side of their axes, and oppositely arranged piston and cylinder devices operatively related to the bell cranks, and an actuating unit including valve controlled fluid-pressure means for said oppositely arranged piston and cylinder devices of the operating 10 unit, said actuating unit also including a cut-off controlled piston and cylinder device for the reciprocating transmitting element.

21. An engine controlling mechanism including, in combination with connections 25 respectively for the throttle and reversing gear of an engine, an operating unit having a transmitting lever for the reversing gear connection, a reciprocating transmitting cam yoke for the throttle connection having a cam engagement with the transmitting lever, and lever actuating means for yieldingly holding the same by steam pressure in position for engagement by the cam yoke, and 30

a fluid-pressure actuating unit for effecting automatic actuation of the transmitting lever and the cam yoke.

22. An engine controlling mechanism including, in combination with connections respectively for the throttle and reversing gear of an engine, an operating unit including 40 a transmitting lever for the reversing gear connection, and a reciprocating transmitting element for the throttle connection having an operative engagement with the transmitting lever, and an actuating unit 45 including fluid-pressure controlling means for that part of the operating unit which operates the transmitting lever in one direction, said fluid pressure controlling means having a distributing valve, and said actuating unit also including a cut-off controlled piston and cylinder device having a rod connection with the reciprocating transmitting element, a fulcrum lever connected with said rod connection and also with the cut-off of 50 said piston and cylinder device, and a manually adjusted setting device having separate adjusting connections respectively with the fulcrum lever and with the distributing valve.

60 In testimony whereof I hereunto affix my signature in the presence of two witnesses.

WALTER W. McBANE.
